UNITED STATES PATENT OFFICE.

O. M. STILLMAN, OF STONINGTON, CONNECTICUT.

IMPROVEMENT IN AIR-ENGINES.

Specification forming part of Letters Patent No. 28,911, dated June 26, 1860.

To all whom it may concern:

Be it known that I, O. M. STILLMAN, of Stonington, in the county of New London and State of Connecticut, have invented certain Improvements in Air or Gas Engines; and I do hereby declare that the following is a full, clear, and exact description of the same, reference being had to the accompanying drawings, in which—

Figure 1 is a vertical section of an air-engine with my improvements attached, and Fig. 2 is a horizontal section of the same through line *x y* of Fig. 1.

Similar letters of reference indicate like parts in both figures.

My invention is applicable to that class of engines in which the same air or other gas is used over and over again, and refers to the means of cooling the air after it has actuated the working-piston in order to reduce its volume for the return-stroke. Several methods have been used for this purpose, one of which is convection by the use of water in contact with tubes through which the air is caused to flow. Where water is sufficiently plenty, this answers every purpose; but as the sensible heat of the water is much increased by a small increment of caloric, and the water can be raised but a few degrees in temperature without decreasing the efficiency of the refrigerator a larger quantity must be used than is conveniently procured in many situations.

My invention consists in moistening the surfaces of the refrigerator and in connection and combination therewith applying power to cause an active circulation of air in contact therewith, whereby a rapid evaporation is induced and the heat removed with the use of a very much smaller quantity of water.

My invention also consists in the arrangement of the refrigerator relatively to the cylinder and piston, whereby the mechanism is simplified and reduced in amount.

To enable others skilled in the art to make and use my improvement, I will proceed to describe its construction and operation by the aid of the drawings and of the letters of reference marked thereon.

A is a cylinder, *B* a piston, and *C* a crank, of an air or gas engine.

C' is the connection from *C* to the cross-head *B''*.

D is the heater, of a tubular or other suit-

able construction for the purpose, and *E F* pipes connecting it with the cylinder.

On the ascent of the piston air is taken in from the reservoir *G* through the self-acting valve *R* into the lower end of the cylinder. On the return-stroke it is compressed by piston *B* and forced into the heater *D*, where it is expanded, and on the opening of a suitable valve (not represented) acts upon the top of piston *B*, giving motion to the engine. It is then exhausted through the pipe *I* and enters the reservoir *G* either with or without first passing through a regenerator. This reservoir is made in the form shown in Fig. 2, with a spiral partition *K* extending several times around the center. The spaces between the partitions are traversed by perpendicular tubes *L*, open at each end and communicating with the atmosphere. Around the exterior of *G* extend one or more coils of pipes *Q*, through the interior of which pipes the reservoir *G* is connected with the exhaust-pipe *I*. The hot air from *I* first traverses through the coils *Q* and then enters *G*, traversing around in the spiral passage. Before it can reach the center of *G* it must pass all the tubes *L* in succession.

The exterior of the reservoir *G* and the interior of the tubes *L* are covered with some porous substance which will hold a small quantity of water and are kept continually moist by water supplied for this purpose. *T* represents this substance.

To the piston-rod *B''*, I attach a vessel *O*, which extends around the reservoir *G*, leaving a narrow annular space *P* between it and *G*. At each revolution of the engine the air contained in *O* is forced out through the tubes *L* and the space *P* over the moist surfaces and a fresh quantity inducted through the same passage, causing a rapid evaporation from those surfaces, and thus reducing their temperature and that of the air which comes in contact therewith. As the water evaporates a fresh supply is provided in any convenient manner. I propose to supply the water at a proper rate by keeping the top of *G* constantly wet and allowing the porous substance to absorb a sufficient quantity by capillary attraction. I can, if preferred, allow the water to flow down in small quantities without any porous conductor.

It is evident that any other convenient

means of causing a circulation of air in contact with the moist surfaces might be used—such as a common bellows or a fan-blower—without altering the nature of my invention.

In my method of cooling only a small portion of the power of the engine is consumed in moving the air, and by reason of the velocity of air actively forced and the rapidity of the evaporation the heat may be conveyed away very rapidly with a much smaller quantity of water than by any means previously known for this purpose.

By my arrangement or the refrigerating-vessel relatively to the other parts the air is blown by the reciprocation of the vessel O, mounted directly upon the piston-rod, thus greatly simplifying the mechanism of the engine.

I am aware that evaporation from moist surfaces has often been used for cooling dif-

ferent substances; but I am not aware that the surfaces of a refrigerator for air-engines have been moistened and a blast of air forced by the working of the engine to circulate in contact therewith for increasing the evaporation, and

I therefore claim as my invention—

1. Using a portion of the power of an air-engine to cool the air used in the same by blowing currents of air over the moistened surfaces of the refrigerating-vessels, substantially in the manner herein set forth.

2. The arrangement of the refrigerating-reservoir G and blowing-vessel O relatively to the cylinder A and piston B, substantially as and for the purposes herein set forth.

O. M. STILLMAN.
